UNITED STATES PATENT OFFICE.

JAMES M. WILSON, OF NEWARK, NEW JERSEY.

MAGNETIC INDUCTOR.

Application filed September 1, 1917, Serial No. 189,251. Renewed October 10, 1923.

To all whom it may concern:

Be it known that I, JAMES M. WILSON, a citizen of the United States, resident of Newark, county of Essex, and State of New Jersey, have invented certain new and useful Improvements in Magnetic Inductors, of which the following is a specification.

My invention relates more particularly to an improved magnetic inductor wherein a constant magnetic field is produced in any suitable manner as for example by a battery current or other suitable source which is adapted to energize magnetic pole pieces and rotary soft iron inductors which are adapted to direct the magnetic flux from the pole pieces through the soft iron core of an induction coil alternately in opposite directions. The soft iron induction coil core is surrounded by suitable windings preferably as primary and secondary coils wherein the primary circuit is adapted to be interrupted intermittently in synchronism with the rotary inductors.

My present device is an improvement upon the battery magnetic inductor shown and described in my Patent No. 1,308,567. In the present construction, the device has been much simplified, and a single pair of electromagnetic pole-pieces is preferably energized by a single battery coil, the axis of which is in a plane at right angles to the axis of rotation of the rotary inductors. The battery pole-pieces are extended longitudinally of the rotary member and provided at either end with pole-faces adapted to co-operate respectively with two pairs of rotary inductors. The pairs of rotary inductors are spaced apart, one being above and the other below the transversely extending battery coil the inductors of each pair being in opposite quadrants and alternating with the inductors of the other pair. In other words, the inductors of one pair are at right angles to the inductors of the other pair.

In this form of my device, I provide a soft iron induction coil core, located at one side of the rotary member and between the electro-magnetic pole-pieces, its axis being parallel with the axis of rotation of the inductors. Pole-pieces are provided at each end of the induction coil core, located respectively in the fields of the two pairs of inductors. The induction coil core pole-pieces are located in the same horizontal

planes with the pole-faces at each end of the battery pole-pieces and 90° therefrom. The angularity may be changed when the device is designed for six cylinder engines.

By this arrangement, it will be seen that as the rotary member is rotated, the magnetic flux of the battery magnet will pass alternately in opposite directions through the induction coil core. The latter is provided with primary and secondary coils which are connected up substantially similar to the connection shown in my previous application hereinbefore referred to.

My improved device is shown in the accompanying drawings in which Fig. 1 represents a vertical section transversely of the magnetic pole-pieces. Fig. 2 represents a vertical section at right angles to the section shown in Fig. 1. Fig. 3 represents a top plan view of the interrupter connections. Fig. 4 is a top plan view of the pole pieces and rotary inductor. Fig. 5 is a plan of the electrical connections, and Fig. 6 is a modified plan of the connections.

Referring to the drawings, 1 represents the cylindrical enclosing case of the device, the lower end of which is closed by a disk forming the base plate 2 of the instrument. The disk 2 is provided with a central boss 3 bored out to form the bearing for the lower end of the shaft 4 of the rotary member. The upper end of the shaft at 5 is preferably of smaller diameter and extends through a bushing 6 in a disk 7 forming the upper or top plate of the instrument. The base plate 2 and top plate 7 are preferably spaced apart and held in parallel relation by the electromagnetic pole-pieces 8 and 9 which are preferably secured to the respective plates by means of screws 10, thereby forming a rigid construction. The pole-pieces 8 and 9 preferably extend vertically parallel with the shaft 5 and are provided with upper and lower pole-faces 11 and 12 adapted to co-operate respectively with two pairs of rotary inductors as hereinafter described. The pole-pieces 8 and 9 are connected by a transversely extending core 13 about which is mounted a coil 14 adapted to be energized from the battery. The core 13 may be set in notches in the pole-pieces 8 and 9 so that the core and coil 14 may be readily removed for repair or replacement when desirable. Opposite the battery coil 14 and between the plates 2 and 7 I prefer-

ably mount a laminated soft iron core 15 provided with pole pieces 16 and 17 secured to the base plate 2 and top plate 7 by suitable screws 16^a. The core 15 may be held in place in the notches of the pole pieces 16 and 17 by suitable screws or rivets 17^a, but if desired the core 15 may be removably fitted into the notches of the pole-pieces to facilitate ready removal of the coils for 10 repairs. Suitable windings such as a primary coil 18 and a secondary coil 19 are mounted on the core 15, forming in the usual way an induction coil. The induction coil core 15 is preferably secured between 15 the plates 2 and 7 in parallel relation with the shaft 5 of the rotary member. It will thus be seen that the axes of the primary and secondary coils are at right angles to a plane through the axis of the battery coil 20 14. The pole-pieces 16 and 17 of the induction coil core are in the same horizontal plane with the respective pole-faces 11 and 12 formed on the electromagnet pole-pieces 8 and 9, and, as indicated in Figs. 4, 5 and 25 6, are 90° from the pole-pieces, or midway between them.

Co-operating with the pole-faces of the battery magnet and with the pole-pieces of the induction coil core, I preferably mount 30 on the rotary member a pair of soft iron inductors. For this purpose, the shaft 5 near each end thereof is provided with a flanged disk 20 and 21 secured respectively to the upper and lower ends of the shaft 5 by suitable pins 22 and 23 as illustrated in 35 Figs. 1 and 2 of the drawings. Each of these disks carries at its periphery a pair of inductors 24 and 25 preferably made up of laminated soft iron. Washers 26 and 27 40 preferably are placed above and below the respective inductors 24 and 25 and secured to the flanged members 20 and 21 by suitable rivets 28 adapted to pass through the ends of the laminated inductors as indicated in 45 Fig. 4 of the drawings, and thereby secure the inductors in proper relation to the shaft 5. The disk members 20 and 21 and washers 26 and 27 are preferably of brass or other suitable non-magnetic material for 50 magnetically insulating the respective inductors 24 and 25. As indicated in the drawings (see Figs. 4 and 5) the upper pair of inductors 24 are in opposite quadrants and alternate with the lower pair of inductors 25, or, in other words, one pair of inductors is at right angles to the other.

From this construction it will be seen 60 that the magnetic flux of the battery magnet will pass through one of the faces 11-12 through an inductor to one of the pole-pieces of the induction coil core 15 and after passing through the induction coil core will again pass through an inductor to the opposite pole of the battery magnet. The 65 pairs of rotary inductors being at right

angles to each other above and below, the magnetic flux from the battery magnet will alternately pass to and from the induction coil core from diagonally opposite pole-faces 11-12. In this way, as the rotary inductors are rotated, the magnetic flux through the induction coil core will alternate in direction four times during one rotation of the rotary member.

The upper end of the shaft 5 is preferably 70 provided with a washer 29 and nut 30 adapted to hold the rotary member in place in its bearings. The extreme upper end 31 of the shaft 5 is turned down and preferably, has mounted thereon a multilobed cam 32 of 80 insulating or other suitable material, a bushing 33 being provided for properly securing the lobed cam to the shaft 31. The cam 32 in the present instance is shown as 85 square (see Fig. 3) and is adapted to co-operate with a circuit breaker or interrupter suitably connected in the primary circuit as indicated in Figs. 5 and 6 of the drawings. Preferably this interrupter comprises a spring 34 secured in slotted studs 90 35 and 36, projecting upward from the top plate 7 as indicated in Figs. 1 and 3 of the drawings. A metal strip 37 is preferably secured to the spring 34 and upon this an insulating strip 38, the metal strip 37 and insulating strip 38 being preferably secured to the spring 34 by means of screws or rivets 95 39. Obviously it is not necessary that both the lobed cam 32 and the strip 38 shall be of insulating material, since if one is of metal, the parts will be sufficiently insulated. A stop pin 40 is provided for limiting the outward movement of the strip 37. The strip 37 is provided at 41 with a contact point 100 adapted to co-operate with an adjustable contact point 42 secured to a bracket 43 projecting upward from the face of the top plate 7. A condenser 44 is preferably connected across the contact points substantially as indicated in Figs. 3, 5 and 6 of 105 the drawings.

An upwardly projecting button 45 of insulating material is mounted upon the top plate 7 as indicated in Figs. 1 and 3 of the drawings and provided with a resilient 110 brush or contact point 46 connected with one end of the secondary of the induction coil. A disk of insulating material 47 is 115 preferably mounted upon the upper end of the shaft 31 of the rotary member by means of a bushing 48 and a screw 49 as indicated in Fig. 1 of the drawings and is thereby adapted to rotate with the rotary member. The underside of this disk is preferably provided with an annular ring 50 adapted to 120 co-operate with the contact brush 46. A contact pin 51 is connected with the ring 50 and projects through the upper face of the disk 47 in position to contact with the 125 socket pieces 52 which as indicated in Figs. 130

5 and 6 of the drawings are adapted to be connected respectively with the spark plugs 53 of a four cylinder engine.

Referring more particularly to Fig. 5 of the drawings, it will be seen that the magnet coil 14 is adapted to be connected with a battery 54, one pole of which is grounded at 55. A switch member 56 is connected at 57 with the line 58 leading to one end 10 of the primary coil 18. The other end of the primary coil is connected by the wire 59 with the contact point 42 of the interrupter, the interrupter spring member 34 being grounded at 60. The connection of 15 the condenser 44 is indicated by the wires 61 and 62 connected respectively with the ground 60 and the wire 59 or contact point 42. The wire 63 leads from the battery 54 to one end of the magnet coil 14, the other 20 end being connected by a wire 64 to the contact post 65 on the switch member. Another contact post 66 is provided and connected with the ground 67. Thus it will be seen that when the switch member 56 is 25 thrown over to cover the contact posts 65 and 66, the battery circuit will be completed through the magnet coil 14 and the two ground connections 55 and 67. At the same time the end 58 of the primary circuit 30 18 is grounded at 67 through the contact 66. The opposite end of the primary circuit is grounded at 60.

The secondary circuit 19 is indicated as connected by a wire 68 with the rotating arm 35 69 which carries a contact pin corresponding with the contact 51 represented in Fig. 1 of the drawings, the four contact sockets 52 being represented as connected with the spark plugs 53. The latter are connected to 40 the ground in the usual manner as indicated by the wire 70 leading to the ground 71, the other end 72 of the secondary coil being also grounded at 71. The relation of the parts is such that the multilobed member 32 will 45 interrupt the primary circuit at the maximum and minimum points of induction and simultaneously the contact member 51 will be in contact with one of the plug members 52, so that a spark will be produced across 50 the gap of the corresponding spark plug.

As described in my previous application hereinbefore referred to, I preferably provide an additional contact 73 in co-operative relation with the switch arm 56 and connected by wire 74 with the battery 54, so that in starting, the arm 56 may be moved over into contact with the button 73 and thus direct the entire battery current through the primary coil 18.

60 In some cases it may be desirable to rearrange the connections as more particularly illustrated in Fig. 6 of the drawings. In this representation, the corresponding parts are indicated by the same characters as in 65 Fig. 5, the main difference being in the

form of switch employed. In this form, the battery 54 is connected by a wire 75 with the center 76 of the switch arm 77 adapted to cover a pair of contact points 78 and 79. The contact point 78 is connected by a wire 80 with one end of the primary coil 18. The contact point 79 by means of an intermediate loop 81 is connected with another contact point 82, the latter being connected by a wire 83 with one end of the battery coil 14, 75 the other end of the coil 14 being grounded at 84. The switch arm 77 is provided on the opposite side on the center 76 with another arm 85 insulated from the arm 77 by an interposed strip of insulation at 86. The switch block is preferably provided with two additional contact points 87 and 88, the latter 88 being connected with the ground at 89. The contact point 87 is connected by 80 means of a loop 90 with the contact point 78, which as previously described, is connected by the wire 80 to the primary coil. With a switch connected in this manner, it will be seen that when the switch arms 77 and 85 are in the position indicated by full 85 lines in Fig. 6, the battery circuit will be divided and part will pass through the magnet coil 14 and part through the primary coil 18, the two being connected in parallel circuit. If, however, the switch arms are 90 thrown to the dotted line position, the entire battery current will pass through the battery coil 14 while the primary coil will be grounded at 89.

In this improved form of my magnetic inductor, I have shown a construction particularly adaptable to four cylinder engines, but obviously, I do not wish to be limited to the specific construction shown, for various modifications in the details of construction 100 may be made in adapting the device to engines of various types without departing from the spirit and scope of the invention. 105

I claim—

1. A magnetic inductor comprising a rotary member, an electro-magnet provided with bifurcated pole-ends, located respectively in opposite quadrants relatively to the axis of said rotary member, similar pole-ends being spaced apart longitudinally of 110 said axis, a battery coil for energizing said pole-ends, said coil being at right angles to the axis of said rotary member, a soft iron induction coil core mounted on the opposite side of the rotary member from said battery coil and parallel with the axis of said rotary member, said core being provided with pole-pieces at each end, located in quadrants between said bifurcated pole-ends, and a pair of segmental inductors mounted on said 115 rotary member for cooperation with said core pole-pieces and the corresponding bifurcated pole-ends at each end of said core, the segmental inductors of each pair being 120 located in opposite quadrants and at right 125 angles to the axis of said core, the segments of 130 each pair being connected in series.

angles to the other pair, whereby the direction of the magnetic flux through the inductors and said induction coil core is adapted to alternate when said inductors are rotated, 5 the flux being through the core and an inductor opposite each of said pole-pieces.

2. A magnetic inductor comprising a rotary member, an electro-magnet provided with bifurcated pole-ends, located respectively in opposite quadrants relatively to the axis of said rotary member, similar pole-ends being spaced apart longitudinally of said axis, a battery coil for energizing said pole-ends, said coil being at right angles to the axis of said rotary member, a soft iron induction coil core mounted on the opposite side of the rotary member from said battery coil and parallel with the axis of said rotary member, said core being provided with pole-pieces at each end, located in quadrants between said bifurcated pole-ends, primary and secondary coils on said core, a pair of segmental inductors mounted on said rotary member for cooperation 25 with said pole-pieces and the corresponding bifurcated pole-ends at each end of said core, the segmental inductors of each pair being located in opposite quadrants and at right angles to the other pair, whereby the 30 direction of the magnetic flux through the inductors and said induction coil core is adapted to alternate when said inductors

are rotated, the flux being through the core and an inductor opposite each of said pole-pieces, and means carried by said rotary member for intermittently breaking the circuit of said primary coil. 35

3. A magnetic inductor comprising a rotary member provided near each end with a pair of magnetically insulated inductors the 40 inductors of each pair being in opposite quadrants and at right angles to the other pair, electromagnetic pole pieces on opposite sides of said rotary member and extending lengthwise thereof provided with pole 45 faces above and below in the field of rotation of the respective pairs of inductors, a core connecting said pole pieces extending transversely of the axis of said rotary member, a battery coil about said core for energizing said pole pieces, an induction coil core parallel with the axis of said rotary member provided with pole pieces at each end, between and 90° from the corresponding magnet pole faces in the field of the 50 respective pairs of inductors, primary and secondary coils about said induction coil core, connections for sending a battery current through said battery coil while the circuit of said primary is closed by grounding 55 and means synchronized with said rotary member for intermittently interrupting the primary circuit. 60

JAMES M. WILSON.
